DENTURE

Charles H. Wharton, Chicago, Ill.

Application November 27, 1931
Serial No. 577,478

8 Claims. (Cl. 32—4)

This invention relates to dentures and particularly to lower dentures of the sectionalized or plural part full denture type, and contemplates an improvement for permitting lateral excursion

5 of the anterior and posterior parts of the denture.

In the embodiment of the invention selected for illustration herein relatively great lateral excursion or lateral swinging movement is permitted along the top or upper edge of the denture part 10 with relatively slight movement along the bottom or foundation engaging base. The appliance is rigidly acting under pressures on the anterior teeth except for lateral excursion of the anterior part on the posterior parts, and this is permitted 15 around low centers. Upon pressure upon the posterior parts only, these parts have freedom for lateral excursion around low centers and when the entire appliance is under pressure lateral excursion of the anterior part relative the posterior 20 parts is through a crank-like action also around low centers, the posterior parts having freedom for lateral excursion about the same low centers at this time.

In addition to the foregoing improvements the 25 appliance of the present invention is so constructed that the masticating pressures on the anterior teeth will be taken care of partly, at least, by the posterior parts of the denture on either side, and the appliance may be so constructed 30 that the posterior parts will begin compression on the posterior tissues before pressure is brought upon the tissues along the anterior part. At the same time the anterior and posterior parts of the denture have relative up and 35 down movement whereby the masticating pressures on the posterior teeth are taken by the posterior tissues without application of objectionable stresses upon the anterior part or upon the anterior tissues therebeneath. Furthermore, the 40 construction is such that compression of the tissues under the posterior part at one side does not produce objectionable stresses upon the tissues along the posterior part at the opposite side.

The sectionalized construction enables providing and maintaining better accommodation to the mouth and enables uni-lateral functioning without bi-lateral stress and, as already pointed out, each posterior part permits of downward pressure independently of the anterior part and 45 the opposite posterior part, thereby enabling the compression of the tissue pad under either posterior part without compressing the tissues under the anterior part or under the opposite posterior part. The sectionalized construction also makes 50 it possible to take the impression of the lower jaw

in different sections instead of in a single impression. This enables taking the impressions of the posterior areas under pressure and separately and with the anterior tissues at rest.

The particular number of parts into which the 60 denture is divided may vary within the scope of the present invention. In the preferred embodiment the denture is made in three parts, right and left hand posterior parts carrying the posterior teeth with a separate anterior part carrying the six lower anterior teeth. The meeting ends of the parts are detachably connected by crank-like connectors which provide low centers 65 of excursion for the posterior parts and through crank-like action relatively great lateral excursion of the upper edge of the anterior part about the same low centers. At the same time the cooperation of the crank-like connectors with the respective denture parts is such as will permit relative up and down movement between the 70 parts, and particularly downward movement of the posterior parts free of the anterior part.

The invention is illustrated in the accompanying drawing, in which:

Figure 1 is a top plan view of an embodiment 80 of the invention;

Figure 2 is a rear elevational view partially in section and taken on the line 2—2 of Figure 1 with the foundation or lower jaw in dotted lines;

Figure 3 is a fragmentary vertical section on 85 an enlarged scale and taken on the line 3—3 of Figure 1;

Figure 4 is a fragmentary horizontal section on an enlarged scale and taken on the line 4—4 90 of Figure 3; and

Figure 5 is a view of one end of the posterior denture part taken substantially on the line 5—5 of Figure 1 and showing one of the eccentric pins of the crank-like connector in section.

Referring to the drawing, the embodiment of 95 the invention illustrated therein comprises right and left hand lower posterior parts 5 and 6 and an intermediate front or anterior lower part 7 disposed therebetween and constituting with the parts 5 and 6 a full lower denture. The part 5 comprises a base portion 8 carrying the right hand posterior lower teeth 9 and the part 6 comprises a base portion 10 carrying the left hand posterior lower teeth 11. The anterior part 7 comprises a base portion 12 carrying the six 105 lower anterior teeth 13.

The base portions 8 and 10 may be of any suitable or preferred material, gold, rubber, and condensites being now commonly used for this purpose. The teeth 9 and 11 and the lower anterior 110

- teeth 13 are rigidly attached to the respective base portions 8, 10 and 12. The bottoms of the base portions 8, 10 and 12 are formed at 15 to conform with the foundation 5 or lower jaw indicated in dotted lines at 16 in Figures 1 and 2. This formation while continuous around the full denture is sectionalized along the joints between the denture parts. The sectional character of the appliance enables taking 10 the impression in separate sections instead of in one impression (as in a one-piece denture), enabling particularly taking the impressions of the posterior areas under pressure independently of the anterior area so that the anterior area may 15 be at rest and without stressing the same with pressure upon the posterior areas. The sectionalized construction also enables better accommodation to the foundation or jaw 16 and permits uni-lateral functioning of the appliance without 20 bi-lateral stress. The posterior base portions 8 and 10 may be formed at 17 and 18, respectively, to grip around the mylohyoid ridge indicated more or less diagrammatically at 20.
- The base portions 8 and 12 abut endwise at 25 25 and the base portions 12 and 10 abut endwise at 26. These abutting ends 25 and 26 preferably are in vertical or substantially vertical planes as indicated by the dot and dash lines 27 and 28.
- The connecting means between the abutting 30 ends 25 and 26 are identical so that a description of the connection between the abutting ends 25 will suffice for both. This connection comprises a flat circular metal disc 30 interposed between the abutting ends of the denture parts 5 and 7 35 and provided with a pair of diametrically opposite eccentric pins 31 and 32, one projecting from one side of the disc 30 into a vertically elongated slot 33 in a flat metal plate 34 secured to the adjacent end of the denture part 5 and the other 40 extending into a vertically elongated slot 35 in a similar flat metal plate 36 secured to the opposed end of the denture part 7. The opposite vertical edges and lower edge of the plate 34 are turned in as shown at 39 in Figure 5 to receive a 45 washer 37 through which the pin 31 projects, and the vertical edges and lower edge of the plate 36 are similarly turned in to receive a washer 38 through which the pin 32 projects. The in-turned edges of the plates 34 and 36 are spaced 50 from the respective plates substantially the thickness of the respective washers to receive and retain these washers which form spacers for properly positioning the disc 30 between the abutting ends of the denture parts. It is understood 55 that these plates may be relatively thin and may be embedded in the ends of the respective denture parts substantially flush with the abutting surfaces thereof, the thickness of the disc 30 preferably being such as to be accommodated and 60 properly operable with the inturned margins 39 of one plate in engagement with the corresponding inturned margins of the adjacent plate.
- The pins 31 and 32 are preferably threaded and nuts 40 are provided for holding the same in 65 place in the respective slots 33 and 35.
- Thin metal strips 42 turned in marginally and suitably secured at 43 to the plates 34 and 36 as shown in Figure 4 cover the slots 33 and 35 and the adjacent ends of the pins 31 and 32 and 70 prevent interference with the action of these pins in the respective slots by the attachment of the plates 34 and 36 to the denture parts 5 and 7. The plates 34 and 36 and the slot and pin enclosing pieces 42 are preferably set into 75 the respective denture parts from the abutting
- ends 25 and may be molded or otherwise secured in place. For the purpose of additionally anchoring the plate 36 and enclosure 42 in the adjacent denture part the back of the enclosure 42 is provided with an anchoring bail 44 embedded in the base portion of the adjacent denture part. The enclosing pieces 42 may be applied and secured at 43 to the plates 34 and 36 after application of the nuts 40.
- As shown in Figures 2 and 3, the pin 31 is normally at the bottom of the vertically elongated slot 33 whereas the pin 32 is normally at the top of the vertically elongated slot 35. The eccentric pin arrangement between the abutting ends 26 is the same. This permits relative up and down movement between the parts, and particularly it permits downward movement of the posterior parts 5 and 6 free of the anterior part 7. As a result masticating pressures on the posterior parts are imposed upon the tissues underlying these parts without stress upon the anterior part or upon the tissues underlying the same, and at the same time pressure upon either posterior part is not transmitted to the opposite posterior part nor to the tissues underlying the same. However, the masticating pressures upon the anterior part are transmitted through the engagement of the upper ends of the slots 35 with the pins 32 and the engagement of the pins 31 with the lower ends of the slots 33 to the 105 posterior parts so that these masticating pressures on the anterior part will be at least partly taken care of by the posterior parts of the denture on each side. The appliance may be so constructed that upon pressure upon the anterior part the posterior parts will begin compression on the posterior tissues before pressure is brought upon the tissues along the anterior part.
- The pins 31 form pivots for the posterior parts 110 5 and 6 and the eccentric arrangement disposes these pivots near the lower edges of the posterior parts so that the upper edges of these parts will have relatively great lateral excursion about the pins 31 with relatively slight movement along 115 the bottoms of the posterior parts about these pins. At the same time the discs 30 and pins 32 form crank extensions for the opposite ends of the anterior part 7 so that upon pressure on the anterior teeth or along the entire appliance the anterior part will have lateral excursion through a crank action about the low centers of the pins 31.
- The appliance is rigidly acting under pressures 120 on the anterior teeth except for lateral excursion or lateral swinging through the crank action of the connectors and about the centers of the pins 31. At the same time the posterior parts when under pressure have freedom for lateral excursion about the pins 31, and when the entire appliance is under pressure the posterior parts 5 and 6 have lateral excursion about the pins 31 and at the same time the anterior part 7 has lateral excursion about these pins through the crank action above described.
- I believe it is broadly new with the present invention to provide a sectionalized denture comprising a plurality of tooth carrying denture parts supplementing each other to constitute a full lower denture with means joining the denture 145 parts and permitting not only free up and down movement between the parts, but also lateral excursion of the parts.
- I believe it is also broadly new to provide low centers for relatively great lateral excursion of 150

- the posterior parts with slight movement along the lower edges of these parts, and particularly for obtaining this relatively great lateral excursion of the upper edges of the posterior parts with slight movement along the lower edges of these parts and at the same time providing for lateral excursion of the anterior part about the same low centers through the crank-like action provided by the connectors between the abutting ends of the denture parts. 5
- The particular construction for accomplishing this and the manner in which interference with the action of the pins in the slotted plates on the ends of the denture parts by the attachment of these plates to the parts is prevented, is another aspect of the present invention. 10
- It will be apparent to those skilled in the art that the teachings of the present invention are broader than the specific embodiment illustrated, and I do not intend to be limited to the specific details shown and described. 20
- I claim:
1. In combination, a pair of denture parts having abutting ends and provided with vertically elongated slots adjacent said abutting ends and a disc disposed between the abutting ends of said parts and provided with eccentric pins engaging in said slots and constituting a compound eccentric permitting lateral excursion and relative vertical movement between the denture parts. 25
  2. In combination, a pair of denture parts having abutting ends, flat plates one on each of said abutting ends, said plates having vertically elongated slots and a disc positioned between said plates and having diametrically opposite pins one extending into the vertically elongated slot of each plate. 35
  3. In combination, a pair of denture parts having abutting ends, flat plates one on each of said abutting ends, said plates having vertically elongated slots, a disc positioned between said plates and having diametrically opposite pins one extending into the vertically elongated slot of each plate, and means covering said slots and preventing interference with the action of said pins therein by the attachment of said plates to the denture parts. 40
  4. A sectionalized denture comprising right and left hand posterior denture parts carrying posterior teeth, an anterior denture part carrying anterior teeth and disposed between and constituting with said posterior parts a full lower denture, relatively low pivots for the posterior parts whereby relatively great lateral excursion of said parts is permitted with relatively slight movement at the bottoms of said posterior parts, and means on said pivots for lateral excursion of said parts. 45
  5. A sectionalized denture comprising right and left hand posterior denture parts carrying posterior teeth, an anterior denture part carrying anterior teeth and disposed between and constituting with said posterior parts a full lower denture, relatively low pivots for the posterior parts whereby relatively great lateral excursion of said parts is permitted with relatively slight movement at the bottoms of said posterior parts, and means on said pivots for lateral excursion of said parts. 50
  6. A sectionalized denture comprising right and left hand posterior denture parts carrying posterior teeth, an anterior denture part carrying anterior teeth and disposed between and constituting with said posterior parts a full lower denture, said denture parts having abutting ends with slots adjacent said ends and crank-like connectors between said parts and provided with eccentric pins engaging in said slots, said slots being elongated vertically for relative vertical movement between the parts and the eccentric pins for the anterior part cooperating with the upper ends of the slots thereof with the eccentric pins for the posterior parts in cooperation with the lower ends of the slots adjacent the ends of the posterior parts. 55
  7. A sectionalized denture comprising right and left hand posterior denture parts carrying posterior teeth, an anterior denture part carrying anterior teeth and disposed between and constituting with said posterior parts a full lower denture, said denture parts having abutting ends with slots adjacent said ends, cranklike connectors between said parts and provided with eccentric pins engaging in said slots, said slots being elongated vertically for relative vertical movement between the parts and the eccentric pins for the anterior part cooperating with the upper ends of the slots thereof with the eccentric pins for the posterior parts in cooperation with the lower ends of the slots adjacent the ends of the posterior parts. 60
  8. A dental plate comprising an intermediate section and a pair of end sections, said sections disposed in end to end abutting engagement with each other and the abutting ends of said sections being provided with crank-like connectors engaging in the abutting ends of said sections to connect the sections together for relative lateral excursion of the sections and for relative vertical movement of said sections in the operation of the denture in the mouth, the sections constituting a complete denture. 65
